INKING EDGES OF SHOE PARTS

Paul H. Dixon, Swampscott, Mass., assignor to
United Shoe Machinery Corporation, Paterson,
N. J., a corporation of New Jersey

Application January 29, 1937, Serial No. 123,021

24 Claims. (Cl. 12—51)

This invention relates to machines for applying ink to the edges of shoe parts. It is herein illustrated as embodied in a machine in which the application of ink is effected to all exposed 5 edges collectively irrespective of their contour.

In many varieties of upper leather which are employed for shoe parts, the coloring matter which is applied to the surface of the leather does not penetrate the whole thickness thereof 10 and, consequently, the color of an edge portion is substantially different from that of the surface with the result that the edge portion is conspicuous in the completed shoe unless previously inked. The word "ink" is used herein generically as indicating any coloring material or 15 dye by means of which coloring of the raw edges may be effected and the invention is not limited to its use for shoe parts, it being generally applicable to a variety of articles of leather and 20 like materials. In shoes of the better grades, the raw edges are usually concealed either by folding the edges or by treating them with heat to shrink the adjacent margin in such a way that, due to a curling of the leather, only the grain 25 surface is exposed. At other times, certain styles of shoes, even though they be of high grade, are made up with raw edges to give a certain ruggedness to the appearance.

It will be understood that the application of 30 ink to these raw edges of various contours is a slow and difficult operation, and that it is almost impossible so to apply the ink to the edges that none will be applied to the grain surface of the leather. The inking of the edge is particularly 35 difficult, for example, in shoe tips, the rear edge of which is serrated or saw toothed in contour.

Aside from the peripheral edges of shoe parts and quite irrespective of the grade of shoes, it 40 is found that the perforations which are frequently used for decoration need to be inked in order that there may not be too much contrast between the relatively light surface of the raw edge and the finished surface of the leather. Then, again, there are many women's shoes in 45 which a cut-out pattern is employed and in which the exposed edges of the cut-out openings have to be inked. Quite commonly this is a hand operation, carried out with the use of a pipe cleaner dipped in the ink and, for this reason, relatively 50 expensive.

These problems have long existed and there is disclosed in Letters Patent of the United States No. 1,285,903, granted November 26, 1918, on the application of L. J. Bazzoni, a method of inking shoe parts in which the flesh surface of the 55

piece of leather is pressed against a saturated, felt-covered roll with sufficient force to cause the ink to be squeezed out of the roll into contact with the edges to be coated. For the protection of the finished or grain surface of the leather, 5 a paper strip is employed which is held in contact with that surface as the flesh surface is pressed against the ink-carrying roll. It will be understood that an application of ink is also made to the whole of the flesh surface of the 10 leather at the same time. This, however, is unimportant because of the fact that this surface is completely covered in the finished shoe and for the further reason that the cost of the ink used in thus coating the flesh surface of the 15 leather is small in comparison with the labor cost involved when the ink is applied manually only to the edges concerned. This method is highly successful so far as the effective application of ink is concerned. It did not, however, go 20 into extensive use, possibly because of the expense of the paper-backing strip which had to be employed.

An object of the invention is to provide an improved machine for carrying out a method of 25 this sort and by means of which ink may be applied to all edges of a piece of stock collectively, either peripheral edges or the edges of openings therein, without soiling the finished surface of the work, and at a single passage of the piece 30 through the machine.

To this end and in accordance with an important feature of the invention, the machine is provided with a work-supporting or abutment roll around a portion of the periphery of which 35 is tightly wrapped an ink-applying belt to hold the work against the roll as it applies ink thereto. With this arrangement, the finished surface of the leather is held tightly against the clean surface of the roll and the ink is applied to the 40 edges of the work. As illustrated, an endless belt is employed which is guided about the work-supporting or abutment roll by means of guide rolls arranged to tension the belt in order to wrap it smoothly and tightly about the work-supporting roll and so disposed with respect to the work-supporting roll that a work-receiving run of the belt is provided on which the operator may position pieces of work which are to be carried between the belt and the roll and thereby 45 inked.

Another feature of the invention resides in the employment of a presser or wringer roll by means of which the belt is pressed firmly against the piece of work and against the supporting roll at 50 55

some point in the progress of the work around the covered portion of the work-supporting roll. By this arrangement, it is possible to utilize a rather hard-surfaced, absorbent applying belt 5 and to employ such a small quantity of ink that the surface of the horizontal run where the work pieces are laid on the belt is substantially dry to the touch. Nevertheless, the action of the wringer roll is to cause a flow of ink around the 10 edges which are to be coated. It will be understood that the tension of the belt wraps it tightly around the work-supporting roll thus holding the finished surface of the work so firmly against the surface of the roll that this flow of ink can- 15 not soil the finished surface.

As illustrated and in accordance with another feature of the invention, the ink-applying belt preferably is provided with an absorbent surface such as a layer of felt combined with a backing 20 of a resilient, impervious material so that when the belt passes under the wringer roll, there is no tendency for the ink to escape through the belt. The ink is further confined by ribs formed along the edges of the belt. This backing is commonly 25 rubber, reinforced with cords to control the longitudinal stretching thereof.

Still other features of the invention reside in the provision of cleaning devices for the surface of the work-supporting roll, which surface 30 has previously been polished so that the ink does not stick to it. These cleaning devices include a scraper for the periphery of the roll, a rotary cleaner associated with the scraper and positioned beyond it, and scrapers for the end surface of the 35 roll. Preferably, the cleaning of the end surfaces is effected by means of trough-like members associated with tubes by means of which the ink removed from the roll is carried back to the absorbent layer of the belt.

40 These and other features of the invention will be best understood from a consideration of the following description, taken in connection with the accompanying drawings, in which

Fig. 1 is an angular view of the machine;

45 Fig. 2 is a vertical section through a stopper for the supply bottle, showing the passageways and the valve therein;

Fig. 3 is an angular view of the scraper and stripper mechanism, detached from the machine;

50 Fig. 4 is a fragmentary view of the belt-tensioning lever;

Fig. 5 is a view of a fragment of the end of the work roll showing a scraper and trough associated therewith;

55 Fig. 6 is a plan view of the machine with portions broken away and in section;

Fig. 7 is a longitudinal, vertical section through the machine;

Fig. 8 is a substantially horizontal section 60 looking down on the scraper for the end of the work roll and the tube associated therewith;

Fig. 9 is a transverse section on the line IX—IX of Fig. 8;

Fig. 10 is a similar section on the line X—X of Fig. 8, and

Fig. 11 is an angular view of a fragment of the end of the scraper for the periphery of the work roll.

70 The application of ink is effected by an endless belt 10 having a surface layer 12 of absorbent material on which ink from a source of supply drips, as will be later described. This layer might be made of sponge rubber, woven fabric or the like, but is herein illustrated as made of sheet felt of 75 rather firm consistency which is supported in

turn on a rubber layer 14 reinforced with cords to increase its strength and reduce the stretch. More cords are provided near the margins than in the central portion. Along its edges, the rubber belt is provided with upstanding flanges 16 5 which prevent any ink from working over the edges of the belt. Cooperating with this belt is a smooth-surfaced work-supporting or abutment roll 20 having a shaft 22 which, at each end, is journaled in a ball bearing, the casing 24 of 10 which is received in a slot 26 formed in the side 28 of a frame 30.

The arrangement is such that the belt is wrapped around a portion of the periphery of the work-supporting roll 20, being guided on rolls 32, 15 34, and 36. The bearings 38 of the roll 32 are received in slots 40 at the front of the frame while the bearings 42 of the roll 36 are received in the slots 26 in the side frames 28. In order to tension the belt, the roll 34 has bearings 44 which 20 rest against the vertical edges 46 of the side frames 28 and which may be depressed by means of a hand lever 50. This lever is provided with a U-shaped portion 52, the forward ends of which are notched at 54 (Fig. 4) to receive opposite 25 pins 56 in the side frames. The inner faces of the U-shaped portion 52 have blocks 58 which rest on the upper sides of the bearings 44 and as the lever 50 is depressed, the belt is tensioned, the lever being held in position by means of a latch 30 bar 60 (Fig. 7) notched to engage the thin edge of a detent 62 secured to the lever 50. This latch bar 60 is pivotally mounted in a bracket 64 secured to the frame 30 and a coil spring 66 is provided to hold the latch bar against the 35 bracket 62 on the lever. Additional pairs of pins 68 (Fig. 1) are provided on the outer faces of the side frames 28 thereby to enable the operator to 40 secure the desired tension of the belt in case it stretches with use.

Pieces of work which are laid on the substantially horizontal work-receiving run 70 of the incoming belt are carried under and around the roll 20 and the tensioned belt is very effective in smoothing wrinkled or twisted pieces as they 45 are presented to the machine. Preferably, the surface of the work-supporting roll 20 is not only smooth but is polished, being kept free from ink in a manner to be later described, and as the grain surface of each work piece is held against 50 this polished surface by the belt, this grain surface is protected from being soiled by the belt.

The mere tensioning of the belt will tend to cause the ink in the absorbent felt layer 12 to be applied to the flesh surface of the work and 55 to the exposed edges thereof but a much more accurate control of the quantity of ink applied to the work is effected by utilizing the belt roll 36 as a wringer roll. To this end, pressure is applied to the bearings 42 for the wringer roll 36 60 by means of cams 72 rotatably mounted in bifurcated crossbars 74 extending between the two portions of each side frame 28 which lie at opposite sides of the slot 26. Easy removal of this roll 36 is facilitated by removable pins 75 holding 65 one end of each crossbar 74. These cams 72 are eccentrically mounted in the crossbars 74 and are provided with sockets 76 so that they may be turned to provide a predetermined pressure on the belt and one equalized at opposite ends of the 70 wringer roll 36 as indicated by index marks 77 on the cams 72. At the line of the bite of the rolls 20 and 36, a very considerable pressure is applied to the belt and to the piece of work supported on the roll 20 thereby compressing both 75

the rubber and the felt, and causing the felt layer to fit very closely around the work piece. As the work approaches this line, the air contained in the pockets between the outside edges of the work 5 piece and the belt, and those formed by the perforations 80 and cut-out openings 82, will be pushed out, and the ink squeezed out of the felt layer by this pressure will flow into the spaces from which the air has been driven, thus effectively inking 10 collectively all the raw edges of either the tips 84, the quarters 86 or any other style of work piece at a single passage of the piece through the machine.

Ink is supplied to the belt from an inverted 15 bottle 98 supported on a stand 92 and delivering ink through a perforated stopper 94 to drip on the felt layer 12 of the belt at a point above the wringer roll 36. An air inlet tube 98 supported in the stopper extends substantially to the top of 20 the inverted bottle and a shut-off valve 100 is provided in the stopper controlling an air passage 102 and an outlet passage 104. The quantity of ink which flows through the outlet passage 104 is controlled by a regulating screw 105. By 25 this means and by regulating the pressure of the wringer roll 36, it is possible and desirable to regulate the operation of the machine so that the surface of the felt layer 12 of the belt 10 at the incoming side feels substantially dry to the touch 30 and so that there is no accumulation of ink at the point 106 where the belt first contacts with the down-going side of the work roll 20. Indeed, with the limited quantity which is thus applied to the belt, the wringer roll will then usually 35 create an accumulation of ink sufficient to ink the edges of the work in an area extending back along the felt layer 12 for only a portion of the wrap of the belt around the work roll 20.

As the work pieces 84 or 86 leave the bite of 40 the rolls 36 and 20, they are stripped from the work-supporting roll by a series of individual stripper fingers 110, pivotally mounted on a cross rod 112 (Fig. 3) and having pointed ends 114 which rest against the surface of the work roll 20. These points are effective to lift the pieces 45 of work 84 or 86 and carry them up to a table 120, which is transparent and may be made of glass or celluloid. If the pieces of work are small, they are allowed to pile up on this table 50 or, if they are of fair size, they are removed one by one as they come into view. The work roll 20 and, hence, the belt wrapped around a portion of it, are kept continually in motion by power supplied through a drive pulley 121 on a drive 55 shaft 122 connected by gears 124 to a counter-shaft and thence by a worm 125 on the counter-shaft to a worm gear 126 on the shaft 22 of the work roll 20. These reduction gears are concealed by a casing 127.

60 In order that there shall be no ink on the surface of the work roll 20 which would be transferred to the grain surface of pieces of work presented to the machine 70, provision is made for scraping or wiping the roll just below the stripper fingers 110. For this purpose, the machine is provided with a scraper 130 in the form of an impregnated leather strip. It has been found desirable to soak the leather strip in some such substance as paraffin in order to keep it in a flexible 65 and slightly slippery condition. This scraper 130 is mounted in a channeled holder 132 which is given a V-shaped form, as shown in Fig. 6, so that the ends of the scraper 130 contact with a slightly lower portion of the periphery of the 70 roll 20 than the center does, thus causing the ink 75

to run toward the ends of this roll. Preferably and as shown, the ends of the scraper strip 130 have depending portions 134 (Fig. 11) which overhang the end surfaces of the roll and wipe any ink which may have run over the ends inwardly thereof, away from the periphery. The channeled holder 132 has reduced ends 133 which are received in grooves 136 (Fig. 3) in carrier levers 140 pivoted at their front ends in the frame sides 28. This pivoting is effected by a fixed stud 142 and a spring-pressed stud 144, the latter having a head 146 by means of which it may be drawn back against the tension of a spring 148 to permit removal of the carrier levers 140 and the scraper 130 associated with them. The rod 112 15 on which the stripper fingers 110 are mounted has recessed ends to engage conical points on said studs 142 and 144 and is held in position by the spring 148. Screwed to the upper edges of the carrier levers are a plate 150 and the transparent 20 table 120 of glass or celluloid, to which pieces of work are delivered as they are stripped from the work roll 20 by the fingers 110.

The pressing of the scraper or cleaner 130 against the work roll 20 is effected by hand screws 25 154 threaded in pivoted arms 156 having overhanging upper ends 158. The lower ends of these arms are pivotally mounted in the frame on studs 160 (Figs. 3 and 8) held in the opposite sides of the frame by nuts 162. As an added precaution, there is mounted on the drive shaft 122 30 a tufted cleaner 164 which may be made of bristles or of yarn and which effectively cleans and polishes the surface of the roll. Any drops of ink or pieces of dirt which may be thrown from 35 this cleaner will be received by a guard 166 attached to the arms 156 and caught in its upturned lower edge 168 which forms a sort of trough.

Having thus provided a fixed cleaner or scraper 40 130 and a rotary cleaner 164 for the periphery of the roll, it becomes desirable to collect ink which may have run over on to the end faces of the work-supporting roll 20. To this end, there is provided a pair of metal tubes 170 the inner sections of which may be made of "Bakelite" and have a cutaway portion 172 (Fig. 5). At their outer ends these tubes have inturned end portions 174. The cut-away portion is so arranged 45 that an edge 173 may be brought to bear against the end surface 175 of the roll 20 to scrape the ink therefrom and any ink which is scraped from that surface falls into a trough formed by the tube 170 and runs out through the inturned end 50 174 onto the absorbent surface of the traveling 55 belt 10. It will be realized that the quantities of ink which are thus removed are very small. Each of these tubes 170 is supported in loops 176 and 178 formed on a carrier 180 so that the tube is 60 slidable and turnable with respect to the carrier. The carrier is mounted on one of the studs 160 and one of a pair of similar studs 182 projecting 65 inwardly from the side frames 28, and, when assembled, a spring 184 urges the carrier toward the end of the roll so that the cut-away portion 65 rests on the end face and is held lightly against the down-going portion thereof. After adjustment thus, the carrier 180 is clamped to the stud 160 by a notched pinch bolt 185 (Fig. 10). The 70 position of the inner cut-away end 172 of the tube 170 is such that any ink pushed over on to the end surfaces 175 by the scraper 130, 134 will be caught and removed by the tubes.

In order to permit ready removal and repositioning of these tubes 170, they are each pro- 75

vided with a clamp 186 having a flat face 188 which is brought to rest on a similar surface 190 formed on the front ends of the carriers 180. The tube is held against endwise movement by a latch comprising a spring-pressed ball 192 entering a socket formed in the under face of the clamp 186. This arrangement enables the tubes 170 to be pulled out of the carriers 180 without the use of any tools and to be readily reassembled therein in exactly the position which they originally occupied. To adjust this position, it is only necessary to loosen the screw 194 in the clamp 186, whereupon the tube may be moved axially or rotatably with respect to that clamp 15 to bring the scraper face 173 of the cut-away portion 172 into contact with the end face of the roll 20.

In using the machine, the quantity of ink is adjusted so that so little is supplied to the absorbent felt surface 12 of the belt that the forward run thereof where it passes over the guide roll 32 feels substantially dry to the touch. The felt surface is quite firm and is rendered more so by the tension applied to the belt by means of the hand lever 50. This lever enables the stretch to be taken out of the belt and the latter to be wrapped so firmly around the periphery of the work-supporting roll 20 that a piece of work is held with its grain surface pressed tightly against the clean, polished surface of the work roll thereby preventing any ink from getting on that grain surface. This tension may be enough to force some of the ink out of the felt surface of the belt to cause it to flow around the raw outside edges 35 of the pieces of work and around the corresponding edges of perforations or cut-out openings. The contour of such edges is immaterial and the saw-toothed edges of the tips 84, illustrated in Fig. 1, are as easily coated as are the smoothly 40 curved edges thereof. Preferably, however, the quantity of ink in the belt is not such that the tension of the belt will satisfactorily coat the raw edges of the work but only so much that, by applying the desired pressure to the wringer roll 36, ink is caused to flow as the individual pieces of work reach the line of bite between that roll and the work-supporting roll or approach closely to it. The operator has only to lay the pieces of work on the in-moving work-receiving surface 70 of the belt and to remove them from the table 120. It will be understood that the whole of the flesh surface of each of the pieces will be coated at the same time that the edge surfaces are being coated, but this is of no consequence because these surfaces are hidden in the completed shoe and the cost of the ink applied thereto is very much less than the extra cost of labor required to ink the edges by hand.

Having described my invention, what I claim as new and desire to secure by Letters Patent of the United States is:

1. In an inking machine, an abutment roll, an ink-applying belt, means for supporting said belt with a portion of the belt contacting the roll in order that pieces of work on the belt may be pressed against said abutment roll, and means for cleaning the surface of said roll while it is out of contact with the work.
2. In an inking machine, a work-supporting roll, an ink-applying belt, guide means supporting said belt constructed and arranged to wrap the belt around a portion of the periphery of the work-supporting roll with the applying surface 70 of the belt against the roll, and means acting

on the uncovered portion of the periphery of the roll for cleaning the surface of the roll.

3. In an inking machine, a work-supporting roll rotatable about a horizontal axis, an endless ink-applying belt, means for supplying ink thereto, a plurality of guide rolls for said belt arranged to wrap the belt around a portion of the periphery of the work roll, one of said guide rolls being positioned a substantial distance in front of the work roll thereby to provide a substantially horizontal work-receiving run of the belt, and means for driving one roll to run the belt toward the work roll.

4. In an inking machine, cooperating rolls, means for urging one roll toward the other, and an ink-applying sheet wrapped around a portion of one of said rolls and comprising a layer of resilient, impervious material and a layer of absorbent work-contacting material.

5. In an inking machine, cooperating rolls, means for pushing one roll toward the other, an ink-applying sheet wrapped around a portion of one of said rolls and comprising a layer of resilient, impervious material and a layer of absorbent material adjacent to the surface of the latter roll, and means for cleaning the peripheral surface of one of said rolls.

6. In an inking machine, a work-supporting roll, an endless belt having an absorbent surface and provided with ribs at the edges of this surface, and means for wrapping said belt around a portion of the periphery of the work-supporting roll.

7. In an inking machine, a work-supporting roll, an ink-applying belt having an absorbent surface, guide rolls for wrapping said belt around a portion of the periphery of the work-supporting roll with the absorbent surface adjacent thereto, means for stripping from the work roll pieces of work which have passed between said roll and said belt, means for pressing the belt firmly against the periphery of the work-supporting roll, and positive means for adjusting the pressure of said pressing means.

8. In an inking machine, a work-supporting roll having a smooth surface, an endless belt having an ink-absorbent surface, rolls for tensioning said belt around a portion of the periphery of said work-supporting roll with its absorbent surface adjacent to said roll thereby to hold a piece of work tightly against the surface of the roll, one of said rolls gripping said belt against said work roll, and means for positively adjusting said gripping roll to wring the ink out of said absorbent surface onto the edges of the piece of work.

9. In an inking machine, a work-supporting roll having a smooth surface, an endless belt having an ink-absorbent surface, means for tensioning said belt around a portion of the periphery of said work-supporting roll with its absorbent surface adjacent to said roll thereby to hold a piece of work tightly against the surface of the roll, means for wringing the ink out of said absorbent surface onto the edges of the piece of work adjacent to the point where the belt leaves the periphery of the work-supporting roll, and means for wiping the uncovered portion of the periphery of said roll.

10. In an inking machine, a work-supporting roll, an absorbent ink-applying belt, guide rolls for wrapping said belt around a portion of the periphery of the work-supporting roll, means for adjusting the position of one of said guide rolls to tension said belt, and adjustable means

- to press one of said guide rolls toward the work-supporting roll to wring the belt.
11. In an inking machine, a work-supporting roll rotatable about a horizontal axis, an endless ink-applying belt having an absorbent surface positioned adjacent to said roll, and a plurality of guide rolls for said belt arranged to wrap the belt around a portion of the periphery of the work roll, one of said guide rolls being positioned a substantial distance in front of the work roll thereby to provide a substantially horizontal work-receiving run of the belt moving toward the work roll and another of said guide rolls acting also as a wringer roll to press the belt against the work roll.
12. In an inking machine, a roll, a scraper for cleaning a surface of said roll comprising a tube, the roll-contacting portion of which is cut away to form an open trough and a scraping edge, and means for supporting said tube for rotation to bring the scraping edge into cooperation with the end of the roll.
13. In an inking machine, a smooth-surfaced work-supporting roll, a belt having an absorbent surface wrapped around a portion of said roll, and means for cleaning an end surface of said roll comprising a trough-like member conducting ink back to the absorbent surface of said belt.
14. In an inking machine, a roll, a scraper for cleaning a surface of said roll and comprising a tubular member part of which is cut away to provide a scraping edge, supporting means for said scraper apertured to receive the tubular member, and a collar clamped to said tubular member having a flat surface cooperating with a surface of said supporting means to determine the relation of the scraping edge to the roll.
15. In an inking machine, a roll, a scraper for said roll comprising a member having a scraping portion and a tubular portion, a support for said tubular portion, and a latch for holding the scraper in a predetermined position with respect to the support and hence to the roll.
16. In an inking machine, a smooth-surfaced work-supporting roll, a belt having an absorbent surface wrapped around a portion of said roll, means for cleaning an end surface of said roll comprising a trough-like member, and a scraper for the peripheral surface of said roll constructed and arranged to conduct ink to the ends of the roll for collection in said end trough.
17. In an inking machine, a frame, a work-supporting roll journaled therein, ink-applying means associated with said roll, and a scraper associated with the periphery of said roll, said scraper being V shaped with its outer ends overhanging the ends of the roll at points lower than its central portion.
18. In an inking machine, a frame, a work-supporting roll journaled therein, ink-applying means associated with said roll, carrier levers

having projecting ends fulcrumed on said frame, a cleaner for the peripheral surface of the roll engaging said levers between the ends thereof, and adjustable pressure members cooperating with the outer ends of said levers beyond said cleaner.

19. In an inking machine, a frame, a work-supporting roll journaled therein, ink-applying means associated with said roll, a cleaner for the peripheral surface of the roll, carrier levers therefor fulcrumed on said frame, and arms cooperating with the free ends of said levers, said arms being pivotally mounted on the frame to swing away from the levers and the work roll.

20. In an inking machine, a frame, a work-supporting roll journaled therein, ink-applying means associated with said roll, work-stripper fingers engaging the upper part of the surface of the roll, a cleaner for the peripheral surface of the roll, carrier levers therefor fulcrumed on said frame, and a table on said levers positioned to receive pieces of work stripped from the roll by said fingers.

21. In an inking machine, a frame, a work-supporting roll journaled therein, an ink-applying belt wrapped around a portion of the periphery of said work-supporting roll to carry a piece of work around said portion, work-stripper fingers engaging said roll just beyond said belt, a cleaner for the surface of the roll, and a table mounted on said cleaner to receive pieces of work from said fingers.

22. In an inking machine, a frame, a work-supporting roll journaled therein, ink-applying means associated with said roll, a cleaner for the peripheral surface of the roll, carrier levers therefor fulcrumed on said frame, and arms cooperating with the free ends of said levers, said arms being pivotally mounted on the frame to swing away from the levers and the work roll and joined by a guard positioned in front of said roll.

23. In an inking machine, a frame, a work-supporting roll journaled therein, an ink-applying belt wrapped around a portion of the periphery of said roll, a scraper for the peripheral surface of the roll after it leaves the belt and work, and a driven rotary cleaner for said surface positioned beyond the scraper with respect to the direction of rotation of the roll.

24. In an inking machine, a frame, a work-supporting roll journaled therein, ink-applying means associated with said roll, a cleaner for the peripheral surface of the roll, work-stripper fingers positioned adjacent to said cleaner, studs in said frame on which the cleaner is pivoted, a rod carrying said stripper fingers, said rod being supported by said studs, and resilient means urging one of said studs toward said finger-supporting rod.

PAUL H. DIXON. 60
